UNITED STATES PATENT OFFICE.

PETER ERIK JOHANSON, OF WARREN, PENNSYLVANIA.

UNIVERSAL TOOL-HOLDER.

1,080,560.

Specification of Letters Patent.

Patented Dec. 9, 1913.

Application filed March 11, 1912. Serial No. 683,044.

To all whom it may concern:

Be it known that I, PETER E. JOHANSON, residing at Warren, in the county of Warren and State of Pennsylvania, have invented 5 certain new and useful Improvements in Universal Tool-Holders, of which the following is a specification.

My invention is an improved holder for screw drivers, gimlets, bits, chisels, and other 10 similar tools, and the invention primarily has for its object to provide a holder having a handle socket in one end, and a tool socket in the other end, the tool socket being preferably of tapering form and communicating 15 with a cross slot into which a projection on the tool shank fits to prevent swiveling of the tool in the socket, in which socket the tool may be held with retaining friction or by a latch device, if desired.

The invention also includes those novel 20 details of construction, combination and arrangement of parts, all of which will be first fully described, then specifically pointed out in the appended claim, reference being 25 had to the accompanying drawing, in which:

Figure 1 is a side elevation of the tool embodying the invention. Fig. 2 is an enlarged 30 vertical longitudinal section of the tool holder proper, taken on the line 2—2 of Fig. 1. Fig. 3 is a cross section on the line 3—3 of Fig. 2. Figs. 4, 5, and 6 are enlarged cross sections on the lines 4—4, 5—5 and 6—6 respectively of Fig. 1. Fig. 7 is 35 a central, horizontal, longitudinal section of the tool shown in Fig. 1 and indicating the manner of removing the tool from the holder when it "sticks", and showing how the removing implement may be used to 40 assist in turning the device when at work.

In the drawings in which like numerals and letters of reference indicate like parts in all the figures, 1 represents the holder, which has a handle socket 2 in its rear end, 45 and a preferably tapering tool socket 3 in its front end. Between the sockets 2 and 3, the holder is transversely bored at 4 and slotted at 5 to form a key hole slot as it

were, the slot 5 projecting slightly into and communicating with the tool socket 3, as 50 best shown in Fig. 2. The tool (which it should be understood may be of any desired kind) is provided with a shank 6 to snugly fit into the socket 3, and it is also provided with a flat projection 7 to enter the slot 5 55 and thereby prevent swiveling of the tool in the socket 3. I prefer to form the socket 3 and tool shank 6 of a tapering shape, whereby the tool will be held in the socket with retaining friction, and if desired a 60 latch device may also be employed to retain the tool. The construction of latch device that I prefer, is best indicated in Fig. 5 of the drawing, by reference to which it will be observed that the holder 1 is bored and 65 tapped at 8 to receive the screw 9 and spring 10, and it is further bored to receive and hold a latch ball 11 that enters a recess 12 in the projection 7 of the tool shank 6 to 70 latch the tool in the holder.

In order to place a tool in the holder it is only necessary to insert the shank 6 into the socket 3 and to cause the projection 7 to enter the slot 5. Ordinarily the tool may be removed by simply pulling it out of the 75 socket, but in practice it not infrequently occurs that the tool will become so tightly set in the socket as to make its removal by a simple pulling operation exceedingly difficult. In order that the tool can be removed 80 from the holder in these cases I provide a tool releasing rod 13 that fits freely into the hole 4, and has a flat end 14 that can be projected into the slot 5, so that by using the rod 13 as a lever as shown in Fig. 7, the 85 tool can be forced out of the holder.

When additional leverage is required to turn the holder as when a boring tool is being used, the rod 13 may be passed into the hole 4, see Fig. 7, and while the operator grasps the handle 15 in one hand to hold the tool to the work, he can at the same time apply a turning force to the tool through the medium of the rod 13.

From the foregoing description taken in 95 connection with the accompanying draw-

ings, it is thought the complete construction, operation and advantages of the invention will be apparent to those skilled in the art.

What I claim is:—

5. In a tool holder, a body having a tool holding socket at one end and a key hole slot passing transversely through the body and connecting with the tool socket and a tool

having a shank to fit said socket with retaining friction, and including a projection from said shank to enter the flat portion only of said key hole slot.

PETER ERIK JOHANSON.
